UNITED STATES PATENT OFFICE.

GUY W. COMER, OF CHICAGO, ILLINOIS.

LAMP-SOCKET SUPPORT.

1,176,203.

Specification of Letters Patent. Patented Mar. 21, 1916.

Application filed April 30, 1914. Serial No. 835,388.

To all whom it may concern:

Be it known that I, GUY W. COMER, a citizen of the United States, and a resident of the city of Chicago, county of Cook, and State of Illinois, have invented certain new and useful Improvements in Lamp-Socket Supports, of which the following is a specification.

My invention relates to lamp socket supports and has for its object the production of a portable bracket which will be capable of a plurality of adjustments and which will be efficient in use.

Other objects will appear hereinafter.

With these objects in view my invention consists in the combinations and arrangements of parts hereinafter described and claimed.

The invention will be best understood by reference to the accompanying drawing forming a part of this specification, and in which—

Figure 1 is a side elevation of a lamp socket support embodying my invention, Fig. 2 is top plan view thereof, Fig. 3 is an enlarged section taken on line $x-x$ of Fig. 1, and Fig. 4 is a section taken on line $y-y$ of Fig. 1.

The preferred form of construction as illustrated in the drawing comprises a pair of clamping jaws 1 and 2 formed of metal. The forward ends of the jaws 1 and 2 are curved for engagement with a supporting element A and the inner or engaging surface of each of said jaw ends is provided with a lining 3 of non-abrasive material, preferably felt. The lining 3 is secured in position at its outer end by means of a back turned flange 4 provided at the outer end of each of said jaws, the inner end of the lining being secured in position by inwardly extending pointed fingers 5 pressed from said jaws and which pierce the lining at the rearward end thereof, as clearly shown in Fig. 3.

The rearward end 6 of the jaw 1 is disposed at right angles to the body of said jaw and loosely engages a slot 7 provided for the reception thereof in the rearward end of jaw 2, the portion 6 being reduced in width for this purpose. Arranged upon the jaw end 6 is a loop 8 of wire which is adapted to serve as a stop in order to limit sliding movement of the jaw end 6 in slot 7 in one direction. Opposite edges of the jaw end 6 are provided with notches or slots

9 adapted for engagement by opposite sides of the loop 8 when turned to the position shown in Fig. 3 in order to lock said loop against relative movement upon said jaw end. When said loop is in engagement with said notches it will be seen that the same will serve as a stop engaging against the adjacent side of the jaw 2 to limit the movement of the rearward end of jaw 1 toward the corresponding end of said jaw 2. By turning the loop 8 so that the major axis thereof is disposed in the same plane as a cross section of the jaw end 6, as clearly shown in dotted lines in Fig. 3, said loop disengages the notches 9, permitting of adjustment of said loop longitudinally of said jaw end. With this arrangement it will be seen that the loop 8 may be adjusted along the jaw end 6 to any desired position in order to limit inward movement of the rearward end of jaw 1 as desired.

The outer or engaging ends of the jaws 1 and 2 are moved toward each other or into clamping relation by means of a bolt 10 and coöoperating nut 11, it being clear that movement of said jaw ends toward each other is effected by threading of nut 11 upon said bolt. Said bolt is provided with a squared portion 12 which engages a perforation of corresponding form in the jaw member in order to lock said bolt against relative rotation in the adjustment of nut 11 thereon. By reason of the adjustable connection between the jaws 1 and 2 which is afforded by the adjustable stop loop 8 and bolt 10 and nut 11 it will be seen that said jaws are rendered capable of engaging with supporting elements of various sizes or thicknesses.

The rearward end of jaw 2 is provided with an angular extension 13 the outer end of which is connected by bolt 14 and co-operating thumb nut 15 with an angular arm 16. Said arm is provided with an elongated slot 17 registering with bolt 14 in order to permit of longitudinal adjustment of said arm relative to the portion 13 as will be readily understood. The opposite end of arm 16 is pivotally connected by means of bolt 18 and co-operating thumb nut 19 with the rearward end of an angular arm 20 which carries at its outer end a lamp socket clamp 21. Said lamp socket clamp is simply a resilient split ring which is of a size adapting the same to snugly embrace a lamp socket B. Said ring is provided with an internal annular groove 22 which is

adapted to engage with the annular bead usually provided upon a lamp socket in order to lock the latter against relative longitudinal movement in said clamp, when the 5 latter is in use.

With the arrangement set forth it will be seen that a lamp socket support is provided wherein a multitude of adjustments is permitted so as to allow a lamp socket to be 10 supported in any position desired. In the adjustment of the support as mentioned the thumb nuts 15 and 19 are loosened, being tightened again in order to lock the parts coöperating therewith in positions of adjustment, after the lamp has been adjusted 15 to the position desired.

While I have illustrated and described the preferred form of construction for carrying my invention into effect, this is capable 20 of variation and modification without departing from the spirit of the invention. I, therefore, do not wish to be limited to the precise details of construction set forth, but desire to avail myself of such variations and 25 modifications as come within the scope of the appended claims.

Having described my invention what I claim as new and desire to secure by Letters Patent is:

30 1. A device of the class described comprising a clamping element consisting of a pair of jaws movable toward and from each other; a stop member mounted on one end of one of said jaws for adjustment longitudinally thereof adapted to engage against the corresponding end of the other of said jaws to limit the movement of said jaw ends toward each other; and means engaging 35 with said jaws intermediate their extremities for moving the opposite ends of said jaws toward each other, substantially as described.

2. A device of the class described comprising a clamping element consisting of a 45 pair of jaws movable toward and from each other; a loop on one end of one of said jaws adapted to engage against the corresponding end of the other of said jaws to limit the movement of said jaw ends toward each 50 other, said first mentioned jaw end having slots spaced along opposite edges thereof for releasable engagement by said loop to lock the latter thereto; and means for moving the opposite ends of said jaws toward each 55 other, substantially as described.

3. A device of the class described comprising a clamping element consisting of a pair of jaws movable toward and from each

other, the rearward end portion of one of said jaws being disposed at right angles to the body of the jaw, said jaw end loosely engaging a slot provided in the rearward end of the other of said jaws; a loop loosely mounted on said angularly disposed jaw end adapted to engage against the slotted end of the other of said jaws to limit the movement of said angularly disposed jaw end in one direction in said slot; said loop, when turned to one position on the jaw end embraced thereby, being locked thereto against relative movement and, when turned to another position on said jaw end, being loose for longitudinal adjustment thereon; and means for moving the opposite ends of said jaws toward each other, substantially as described. 75

4. A device of the class described comprising a clamping element consisting of a pair of jaws movable toward and from each other, the rearward end portion of one of said jaws being disposed at right angles to the body of the jaw, said jaw end loosely engaging a slot provided in the rearward end of the other of said jaws; a loop loosely mounted on said angularly disposed jaw end adapted to engage against the slotted end of the other of said jaws to limit the movement of said angularly disposed jaw end in one direction in said slot, said loop, when turned to one position on the jaw end embraced thereby, being locked thereto against relative movement and, when turned to another position on said jaw end, being loose for longitudinal adjustment thereon; opposite edges of said jaw end being notched for engagement by said loop when in operative position; and means for moving the opposite ends of said jaws toward each other, substantially as described. 85

5. A device of the class described comprising a clamping element; a plurality of pivotally connected arms connected with said clamping element; and a socket clamp supported by said arms, said socket clamp consisting of a resilient split ring having an annular internal groove for engaging with the bead on the lamp socket, substantially as described. 100

In testimony whereof I have signed my name to this specification in the presence of 110 two subscribing witnesses.

GUY W. COMER.
